INVENTOR

Edwin P. Hayes
By his Attorney
(John C. Perkins)

UNITED STATES PATENT OFFICE.

EDWIN P. HAYES, OF DEER LAKE, MICHIGAN.

TRIP-SAW.

SPECIFICATION forming part of Letters Patent No. 328,486, dated October 20, 1885.

Application filed August 11, 1885. Serial No. 174,158. (No model.)

To all whom it may concern:

Be it known that I, EDWIN P. HAYES, a citizen of the United States, residing at Deer Lake, in the county of Lake and State of Michigan, have invented certain new and useful Improvements in Trip-Saws; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 Figure 1 is a front view of saw-frame, showing my invention. Fig. 2 is a side view of same.

Similar letters refer to similar parts.

My invention has for its object a simple and inexpensive way of raising cut-off saws above the saw-table by means of a lever, friction-wheel, and cam, as hereinafter described. The saws, when my device is not applied, run below the table, leaving the same free for other uses and the saws out of the way. The cutting capacity of the saws is also greater than where hung in the ordinary manner, and they are less liable to be injured.

I describe my invention as follows: To the upright posts H H are fastened the standards F F, by means of the pillow-blocks G G, said standards being bound together at the top by the girder E and at the bottom by the girder L, said girder E having suitably journaled thereon the shaft B, provided with the pulley C and carrying the circular saws A A. Midway of said standards are the blocks i i, serving as journals for the shaft K bearing the pulleys J, and at the lower ends of said standards, journaled in the blocks f f, is the shaft M, bearing the pulley N. The foregoing constitutes the saw-frame, power being applied thereto through the belt D, I being the tightener and a the support thereof.

45 The foregoing mechanism as shown and described is not claimed as original, and it is only in combination of the same with that hereinafter described that my invention consists.

50 Below the saw-frame just described, held in the journal-blocks c c, is the shaft P, bearing the cam-wheel O, its face meeting that of the pulley N, and on the end of said shaft is the wheel Q. Still farther below, on said posts H 55 H, are the journal-blocks S S, carrying the

shaft V, upon one end of which is the friction-wheel R, adapted to be raised to meet the wheel Q, the block S nearest said friction-wheel being movably adjusted to the post by a screw passing through the slot T, and raised 60 or lowered by the lever U. The other end of the shaft V carries the wheel W, on which is the belt e for the application of power.

It will be seen that when the friction-wheel is raised by the lever U into contact with the 65 wheel Q, turning the shaft P, bearing the cam O, the action of said cam raises the saw-frame, which drops again of its own weight as the cam goes by, thus alternately raising and lowering the saws. The said lever U is extended 70 upward through the floor of the mill, so that it can conveniently be operated by the hand or foot of the sawyer in any convenient fashion.

Having thus described my invention, what I 75 claim, and desire to secure by Letters Patent of the United States, is—

1. The combination of the saw-frame, held and having a perpendicular motion in the blocks G and G, with the shaft P, journaled 80 in the blocks c e, and carrying the cam O and the wheel Q, and operated by contact with the friction-wheel R on the shaft V, adapted to be raised or lowered by means of the lever U, attached to the journal-block S, having 85 the slot T, as described, and for the purpose specified.

2. In a trip-saw machine, the combination of the wheel Q on the shaft P, suitably journaled, the cam-wheel O, the friction-wheel R 90 on the shaft V, journaled in the blocks S and S, having the slot T, with the lever U, as shown and described.

3. The combination of the saw-frame bearing the saws a a, held and capable of perpendicular motion in the blocks G G, and provided at the bottom with the shaft M, journaled in the blocks f f and carrying the pulley N, the shaft P, suitably journaled, carrying the wheel Q, and the cam O, bearing on 95 100 said pulley N, with the friction-wheel R on the shaft V, the journals S and S, having the slot T and the lever U, all substantially as shown, and for the purpose specified.

In testimony whereof I affix my signature in 105 presence of two witnesses.

EDWIN P. HAYES.
